UNITED STATES PATENT OFFICE.

DOCTOR FRANKLIN OLIVER, OF OAKLAND, CALIFORNIA; LILLIE F. OLIVER EXECUTRIX
OF SAID DOCTOR FRANKLIN OLIVER, DECEASED.

SHOCK-ABSORBER.

1,260,018.

Specification of Letters Patent.

Patented Mar. 19, 1918.

Application filed August 20, 1914, Serial No. 857,688. Renewed August 18, 1917. Serial No. 186,923.

To all whom it may concern:

Be it known that I, DOCTOR FRANKLIN OLIVER, a citizen of the United States, and a resident of Oakland, in the county of Alameda and State of California, have invented a certain new and useful Improvement in Shock-Absorbers, of which the following is a specification.

My invention relates to means for resisting jars and shocks, and one of the main objects thereof is to provide such devices which not only resist shocks but which yield to the shock inversely to the force thereof; a further object is to provide such devices which are normally non-resistant, the resisting elements being only brought into action by sudden jars or shocks, thereby permitting a normal, uninhibited, movement of the parts upon each other; a further object is to provide such devices which are based upon the tendency of stationary objects to remain in a state of inertia, and resisting effort to overcome such inertia; a further object is to employ the principle of a wedge of elastic material in producing the desired results; and further objects are to provide such devices which are simple in construction and installation, positive in action, composed of few parts not likely to get out of order to require repair, adaptable to many uses, and comparatively inexpensive.

My invention is fully described in the following specification, of which the accompanying drawings form a part, in which like reference characters are used to designate like parts in each of the views, and in which:—

Figure 1 is a central, longitudinal section taken through one form of embodiment of the principles of my invention;

Fig. 2 is a perspective, detached, view of a pair of similar elements which I employ;

Fig. 3 is a perspective, detached, view of a plunger which I employ, and partly in section;

Fig. 4 is an elevation of a vehicle spring provided with my invention, in position for use as a shock absorber;

Fig. 5 is a view, similar to Fig. 1, but showing a modification in structural details thereover; and

Fig. 6 is a section taken on the line 6—6 of Fig. 5.

In Figs. 1 to 4, inclusive, I have illustrated one form of my invention comprising a shell

or casing 7, preferably angular in cross-section, square as shown, closed at one end and forming a point 8, and provided with a removable cap 9 at the opposite end having an angular opening therethrough for the passage of a plunger 10 inclined at its forward end on opposite surfaces, 11 and 12, forming shoulders 13, to the rear thereof, and 14 to the forward portion 15 thereof, and said plunger 10 is centrally and longitudinally bored to receive a rod 16 having an enlarged head 17 and a spring 18 thereon interposed between said head and the end 15 of the plunger.

Arranged opposite to each other within the casing 7 are two similar friction elements comprising, each, a main plate 19 bearing against the corresponding inner wall of the casing, and bent into a loop 20 to form a rearward directed plate 21 in turn bent toward the center of the casing to form a perpendicular flange 22 having a groove 23 therein of a width equaling the diameter of the plunger 10 which slides therein, in each of the elements, said flanges, however, being close together whereby the space formed by the grooves 23 is much narrower than the lengths of said grooves, the distance between the bottoms of said grooves approximately equaling the thickness of said plunger in the positions of the wedge surfaces 11 and 12 where they most nearly approach each other, said elements being formed of spring metal so that the engagement of the same with said wedge or inclined surfaces is insured at all times, and each of said elements is also provided with a perpendicular member 24 fitting into a recess 25 in the other elements, and jointly forming a passage for the body portion of the plunger whereby said elements are positioned with respect thereto.

As shown in Fig. 1, the device is mounted upon a door 26 and is adapted to impinge on a striking-plate 27 on the door frame 28 in the action of the door spring, not shown, to close the door; when the plunger 10 strikes the plate 27, said plunger is forced inwardly at a speed determined by the force of the impact and, if this be light, the elements move freely with the plunger and without any effect on the former but, if the impact be sharp, the normal frictional contact of the plate portions 19 of said elements tend to hold the said elements stationary, with the

result that the wedge formed by the inclined surfaces 11 and 12 moves forwardly between the said elements and forces the same apart, but against the resiliency of the metal of which they are composed, and the plates 19 bind against the corresponding walls of the casing and the door is abruptly stopped; upon continued pressure of the door, however, the inertia of the said elements is overcome, as well as the friction between the same and the walls of the casing, and the elements move with the plunger to permit the closure of the door.

In the backward plunger movement, upon the release thereof in the opening of the door, the frictional grip between said elements and casing walls is broken by reason of the fact that the inclined plunger surfaces 11 and 12 move from between the elements thus relieving the same of the wedging effect, and said elements move freely with the plunger as it resumes normal position due to the spring 18, ready for another actuation.

25 The above result is rendered possible by reason of the fact that the spring resistance of the elements' plates 21 is less than the inertia of the elements plus frictional contact with the casing walls, and the plunger wedge increases this frictional contact but, as the casing interior is smooth, as are also the element plates 19, pressure eventually prevails and the elements move with the plunger, but at a speed in inverse ratio to the force of 35 the impact and continued pressure, or, in other words, at a speed determined by the distance which the wedge of the plunger had moved between the elements previous to overcoming the inertia and frictional resistance of the latter.

In Fig. 4 I have shown the device attached to the upper member 29 of an elliptical spring, with the plunger downwardly directed and adapted to strike a plate 30 on the member 31 of said spring, and the relationship of the parts of my device, when used as an automobile shock absorber, is such as to allow normal spring action for easy riding, but to resist sudden jars or shocks due to road inequalities, stones, or other impacts, and, in this connection, it will be noted that my device differs from the shock absorbers now in use on automobiles in the fact that the latter are at all times 55 resistant to movement of the parts thereof, but in varying degrees, whereas my device is non-resistant except under shock.

In Figs. 5 and 6 is shown a structural modification, although the same principles 60 are involved, comprising a casing 32 closed at one end and having a detachable cap 33 at the opposite end, and within which cap rests an internally threaded sleeve 34 adjustably mounted on the threaded portion 65 35 of a plunger 36, a lock-nut 37 being used

to lock said sleeve and plunger together when a desired adjustment thereof with respect to each other has been effected.

The forward end of the plunger is formed into a head 38, reduced neck 39, and conical portion 40, and said plunger is bored to receive a rod 41 having a head 42 and coil spring 43 thereon, in the manner described; within the casing 32, incircling the plunger, are a plurality of frictional elements 44, of elastic material 6 as shown in Fig. 6, normally resting against the interior of the casing 32, cylindrical in this form, and collectively forming a bore divided into three parts, 45, 46, and 47, of which the first and last are parallel with the plunger proper and of an internal diameter permitting free movement of said plunger, whereas the part 46 is conical and inclined in the direction and in the degree of the conical portion 40 of the plunger, and it will be seen that precisely the same results follow sudden shock on the plunger's outer end as already described at length with reference to the form shown in Fig. 1, the elements 44 being free to move outwardly independently of each other but being collectively moved longitudinally of the casing 32.

It will thus be seen that I provide a device which normally is not brought into action in the movement of an auto body with respect to its running gear, but which positively resists shocks, and, immediately after the impact of such shock on the device, gradually yields to continued pressure, the speed of such yielding being determined by the force of the shock.

While I have illustrated two forms of application of the principles involved, it will be evident that I am not limited thereto, but may make many changes thereover, within the scope of the following claims, without departing from the spirit of my invention, or sacrificing its advantages.

Having fully described my invention, what I claim as new, and desire to secure by Letters Patent, is:—

1. A device of the class described, comprising a casing, a tapered plunger movable therein, and resilient elements interposed between the tapered portion of said plunger and said casing, said elements yielding under sudden forward movement of said plunger in the degree of the resiliency thereof and binding on the inner walls of said casing in the degree of resistance of resiliency.

2. A device of the class described, comprising a casing, a tapered plunger movable therein, and resilient elements interposed between the tapered portion of said plunger and said casing, said elements yielding under sudden forward movement of said plunger in the degree of the resilience thereof to bind on the inner walls of said casing, and returning to normal positions through said

resiliency under steady forward movement of said plunger.

3. A device of the class described, comprising a casing, a tapered plunger movable therein, a looped sheet metal plate bearing against said casing on each side of said plunger, the looped portion thereof bearing against the respective side of the tapered portion of said plunger.

10 4. A device of the class described, comprising a casing, a tapered plunger movable therein, and provided with a shoulder at the base of said tapered portion, a looped sheet metal plate bearing against said casing, the 15 looped portion thereof bearing against the respective side of said plunger, and means on said looped portions for engagement with said shoulder to limit the plunger movement with respect to said plates.

20 5. A device of the class described, com-

prising a casing, a tapered plunger movable therein, and elements interposed between the tapered portion of said plunger and said casing, said elements being of resilient nature and resisting steady pressure of said 25 plunger to prevent binding of said elements with said casing, and the pitch of said tapered portion being sufficiently sharp to prevent normal yielding of said elements, whereby said plunger and elements are 30 freely movable in said casing under steady plunger pressure, but bind with respect to said casing under plunger shocks.

In testimony whereof I have signed my name to this specification in the presence of 35 two subscribing witnesses.

DOCTOR FRANKLIN OLIVER.
